CLAIM

The ornamental design for an electric bicycle, as shown and described.

DESCRIPTION

FIG. 1 is a top-front-left side perspective view of an electric bicycle embodying our new design;

FIG. 2 is a bottom-rear-right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged-partial perspective view of area 9 in FIG. 1;

FIG. 10 is an enlarged-partial perspective view of area 10 in FIG. 1;

FIG. 11 is an enlarged-partial perspective view of area 11 in FIG. 1;

FIG. 12 is an enlarged-partial perspective view of area 12 in FIG. 2; and,

FIG. 13 is an enlarged-partial perspective view of area 13 in FIG. 2.

The dot-dash broken lines indicate the boundaries of enlarged areas shown in corresponding figures. These broken lines do not represent structure and are not part of the claimed design; rather they are included solely to illustrate the portions of the design that are depicted in greater detail in other views. The features within the broken-line boundaries remain part of the claimed design.
